FLASHLIGHT

John C. Schmidt, Chicago, Ill., assignor to Zenith Radio Corporation, a corporation of Illinois

Application March 15, 1955, Serial No. 35,052

Term of patent 14 years

(Cl. D48—24)

FIG. 2

The bottom of the flashlight is unornamented.

I claim:

The ornamental design for a flashlight, substantially as shown and described.
